UNITED STATES PATENT OFFICE.

ALBERT E. ROBINSON, OF CINCINNATI, OHIO, ASSIGNOR TO THE AMERICAN TOOL WORKS COMPANY, OF CINCINNATI, OHIO, A CORPORATION OF OHIO.

TABLE-SUPPORT.

1,125,401.

Specification of Letters Patent. Patented Jan. 19, 1915.

Application filed July 8, 1914. Serial No. 849,671.

To all whom it may concern:

Be it known that I, ALBERT E. ROBINSON, a citizen of the United States, and residing at Cincinnati, in the county of Hamilton and State of Ohio, have invented a new and useful Improvement in Table-Supports, of which the following specification is a full disclosure.

My invention relates to an improvement 10 in table supports for shaping machines.

An object of the invention is to provide the table of a shaping machine with an extensible leg member or standard adjustably mounted within the table and capable of 15 being rigidly secured thereto.

Another object of my invention is to provide an extensible table support for a shaping machine with a combined adjustment, one for securing a quick and approximate 20 setting, and a second for a minute and precise adjustment.

Another object of my invention is to provide a cylindrical support for the protruding end of the table of a shaping machine, 25 transversely movable thereon and adapted to be positively locked to the table at predetermined positions and releasable by a rotative motion, in combination with means for rigidly clamping the same in any position.

Various other features of my invention relate to structural details as illustrated in the preferred embodiment thereof in the annexed drawings, forming a part of this 35 specification, and from the following description thereof, and in such drawings like characters of reference denote corresponding parts throughout the several views of which:—

Figure 1 is a front elevation of the lower portion of a shaper with my improved table support applied. Fig. 2 is a mutilated side elevation thereof, with portions shown in section. Fig. 3 is a section on line 3—3, 40 Fig. 2.

It is a well recognized expedient to support the free end of a laterally projecting work supporting table of a shaping machine

to increase its stability and relieve the carriage and saddle of excessive downward 50 pressures or strains, and further, to maintain the alinement of the table, justifying accuracy in machining work.

With my improved support, the table alinement can be delicately maintained, as 55 the support is readily extensible to the various heights at which the table may be adjusted, and accomplished by a compound adjustment, one which is quickly and positively made, following with a second of 60 micrometer precision.

The coarse or quick adjustment is in predetermined divisions, by a toothed engagement between the table and support, which is releasable upon a partial rotation of the 65 support, and the second and finer adjustment by a shoe screw threaded upon the end of the support.

The shaper may be of any special or conventional design, and as the invention herein is not concerned with the construction of a shaper, detailed description of its complete organization is herein omitted, except as to such parts as are essential to aid in a clear understanding of the invention. 70

The general organization of the shaping machine, to the extent herein illustrated, comprises a main frame 1, having a forwardly extended base 2, its upper forward margin finished or planed to provide a rail 80 or track 3. The forward surface of the frame has the usual ways or rails 5, 6, vertically extended, upon which the saddle 7 is movably mounted, and raised or lowered by the lifting screw 8. The saddle 7 supports 85 the transversely movable carriage 9 fed either by hand or power by the usual cross feed screw. A table 10 is supported in the usual manner upon the carriage and rigidly clamped thereto projecting laterally therefrom, and its surface is provided with the longitudinal work holding T-slots or grooves. The table represents a hollow casting having a base wall or web 12, cast integral therewith, with a vertical bearing or 90 sleeve extension 13 integrally formed with

the web at the central forward portion thereof. A bar 14 representing the table support or standard is slidably mounted within said sleeve extension. It is provided with a series of equally spaced transverse notches or recesses 15, along a longitudinal line, the equivalent of a rack, into which the toothed plunger 16 engages. The plunger 16 is slidably mounted in a bore of the boss extension 17 formed integral with the web 12, and also yieldingly urged toward the axis of the supporting bar 14 by a spring 18, fitting within the boss bore and retained therein by cap screw 19. The plunger or tooth intermeshing with the supporting bar 14 provides a quick and definite adjustment for the bar and unites the bar with the table without the use of auxiliary hand tools for clamping or releasing. A slight rotation of the bar 14 depresses the plunger within its bore and brings the plunger into engagement with the smoother peripheral surface of the bar which is unobstructing to the movements of the bar longitudinally. The definite spacing of the notches provides interlocking points for adjusting the bar to an approximate degree between the base rail and table with the final or delicate adjustment produced by the extensibility of the bar, which herein is accomplished in providing the bar with a shoe 20 screw threaded thereon. The shoe is horizontally split toward one end, producing a clamping element 21 for frictionally clamping the shoe upon the bar after a proper adjustment has been made, the clamping element being engaged by clamping or tightening screw 22. The shoe rests and slides upon the track 3 and is secured against removal from the bar by means of the washer 23, fitting over the end of the bar. The opposite end of the bar has a similar provision to prevent its removal from the sleeve.

I have provided means for frictionally clamping the bar against rotation within the table sleeve, preferably as illustrated in Fig. 3, although it is obvious that the clamping may be variously accomplished. The construction illustrated comprises a pair of opposing clamping members 24, 25, slidably mounted within a bore formed in the table head, transverse to the bar 14. The member 24 is in the nature of a bolt, its head provided with a recess of a radius approximately that of the bar 14, so as to engage therewith, and a screw threaded shank concentrically extended through the tubular clamping member 25, which is likewise recessed to engage with the bar 14. A nut 26 engages with the shank of the bolt clamping member 24 and against one end of the clamping member 25, so that when the nut is tightened it will draw the clamping mem-

bers toward each other upon opposite sides of a diametric line of the bar to frictionally clamp the bar against movement in any direction.

From the foregoing it will be apparent that I have provided a table of a shaping machine with an extensible supporting member adjustably secured upon the table, the adjustment being preferably in predetermined definite divisions or graduations of table adjustment toward and from the base, to positively secure the support against vertical movement releasable by a slight rotation with the support capable of being rigidly clamped against rotation.

Having described my invention, I claim:—

1. A machine of the class described combining a frame, a table support upon and projected from said frame, an extensible supporting member having indentations along a longitudinal line thereof for intermeshingly engaging with said table, releasable by a partial rotation, and a shoe screw threaded upon the end of said member adapted to engage and slide upon the base of said frame. 80

2. A machine of the class described combining a frame, a table support upon and projected from said frame, an extensible supporting member having indentations along a longitudinal line thereof for intermeshingly engaging with said table, releasable by a partial rotation, a shoe screw threaded upon the end of said member adapted to engage and slide upon the base of said frame, and means for clamping said member rigidly to said table. 90

3. A machine of the class described combining a frame, a table support upon and projected from said frame, an extensible supporting member having indentations along a longitudinal line thereof for intermeshingly engaging with said table, releasable by a partial rotation, a shoe screw threaded upon the end of said member adapted to engage and slide upon the base of said frame, and means for clamping said shoe against rotation. 105

4. A machine of the character described combining a projected member, and an extensible supporting member therefor, interlockingly engaged therewith and releasable by a partial rotation for varying its supporting length. 115

5. A machine of the character described combining a projected member, and an extensible supporting member therefor, interlockingly engaged therewith and releasable by a partial rotation, and provided with a shoe screw threaded thereon for varying its supporting length. 120

6. In a machine of the character described combining a projected member having an

apertured bearing, an extensible supporting member projected through the bearing aperture, and means for binding said member within its bearing releasable by a partial rotation to vary its supporting length.

7. A machine of the character described combining a table, and an extensible supporting member interlockingly engaged therewith, releasable by a partial rotation

for arbitrarily varying its supporting length.

In witness whereof, I hereunto subscribe my name, as attested by the two subscribing witnesses.

ALBERT E. ROBINSON.
